UNITED STATES PATENT OFFICE.

NICHOLAS N. COROTNEFF, OF NEW YORK, N. Y.

DESIGN FOR A BOTTLE OR SIMILAR CONTAINER.

Application filed December 18, 1928. Serial No. 29,324. Term of patent 14 years.

To all whom it may concern:

Be it known that I, NICHOLAS N. COROTNEFF, a citizen of Russia, residing at New York city, county of New York, borough of Manhattan, and State of New York, have invented a new, original, and ornamental Design for Bottles or Similar Containers, of which the following is a specification, reference being had to the accompanying drawing, forming a part thereof.

I claim:

The ornamental design for a bottle or similar container, as shown.

NICHOLAS N. COROTNEFF.
